DOORSTOP

Merrill H. Smith, Athens, Tenn.

Application September 3, 1947, Serial No. 772,687

2 Claims. (Cl. 292—70)

1

This invention relates to door stops.

It is an object of the present invention to provide a door stop which is retractible into the floor when the door is closed and which is automatically raised or lifted for engagement with the door as the door reaches the station where it is to be retained.

Other objects of the present invention are to provide a door stop unit which can be easily installed in the floor and upon the door which is of simple construction, durable, inexpensive to manufacture and efficient in operation.

For other objects and for a better understanding of the invention, reference may be had to the following detailed description taken in connection with the accompanying drawing, in which

Fig. 1 is a fragmentary and sectional view taken through the door stop with the armature raised for connection with the door to retain the door.

Fig. 2 is a fragmentary sectional view taken on line 2—2 of Fig. 1.

Fig. 3 is a fragmentary and bottom plan view of the door with the magnet mounted in it.

Fig. 4 is a fragmentary and top plan view of the floor and of the armature mounted in the same.

Fig. 5 is a fragmentary side elevational view of a modified form of armature which is provided with a raised center portion for added holding capacity.

Referring now to the figures of the drawing, 10 represents a floor about which there is swung a door 11. In the floor 10 there is located an opening into which is extended a sleeve 13. This sleeve is flanged as shown at 14 to limit its downward movement through the floor. At the top of the floor there is a large diameter recess 15 adapted to receive the flange forming the top 16 of a plunger 17 slidable in the sleeve 13. The top 16 and plunger 17 is formed of magnetic material and serves as an armature to be lifted by a permanent magnet 18 fitted in the door 11 and retained therein by a long wood screw 19. The magnet may be of U-shape and is made sufficiently strong so that it will automatically lift the top 16 and the plunger 17 whereby to provide a connection between the door and the floor to retain the door at the particular station to which it has been moved. The screw extends through a block 21 and through a hole 22 in the magnet 18. The block 21 may be made of brass or other non-magnetic material.

As shown in Fig. 2, the top 16 and the plunger are preferably of integral formation. The magnet is sufficiently strong to retain the door but can be separated from the armature by applying added pressure to the door. When the door

2

moves away from the armature automatically the same will drop downwardly into the floor and be concealed therein flush with the floor surface.

In Fig. 5 there is shown a modified form of armature and plunger wherein a cone formation 24 is provided in the center of the top plate so as to give added holding capacity. In this instance the head of the screw 19 is seated in a counterbored opening formed in piece 21 to receive the cone formation 24.

While various changes may be made in the detail construction, it shall be understood that such changes shall be within the spirit and scope of the present invention as defined by the appended claims.

I claim:

1. A door stop comprising a sleeve adapted to be fitted into a floor, an armature vertically movable in the sleeve and adapted to lie flush with the floor surface when lowered, a magnet adapted to be fitted into a door at its bottom edge, said magnet having its end faces lying flush with the bottom of the door and adapted to elevate the armature from the floor when the door is extended thereover, said armature having a large diameter top portion adapted to fit a recess in the floor as the armature is lowered, said magnet being of U-shape and having a central opening adapted to receive a single wood screw, a piece fitted between the ends of the magnet and having a hole aligned with the opening in the magnet, and a wood screw extending through the piece and the magnet and adapted to be extended into the door to retain the magnet therein.

2. A door stop comprising a sleeve adapted to be fitted into a floor, an armature vertically movable in the sleeve and adapted to lie flush with the floor surface when lowered, a magnet adapted to be fitted into a door at its bottom edge, said magnet having its end faces lying flush with the bottom of the door and adapted to elevate the armature from the floor when the door is extended thereover, said armature having a large diameter top portion adapted to be lowered into a recess on the floor and a raised formation in the center of the top portion adapted to enter the magnet to provide added holding capacity between the door and the armature.
